Attorney

UNITED STATES PATENT OFFICE

MILLARD F. WATERS, OF TULSA, OKLAHOMA, ASSIGNOR TO HANLON-WATERS, INC., OF TULSA, OKLAHOMA

GAUGE COCK

Application filed June 16, 1930. Serial No. 461,471.

My invention consists in new and useful improvements in a gauge cock for boilers and the like and has for its object to provide a device for determining the water level in boilers, and equipped with a novel, elongated, cylindrical sealing bar whereby a maximum number of renewable seats may be had for sealing the nipple of the gauge cock.

Heretofore, with gauge cocks employing sealing devices of conventional form, considerable trouble had been experienced from corrosion due to bad water in the boiler, which often makes it difficult to change the sealing device to a new seat. With my improved structure, no matter how badly the device has become corroded, the sealing member is so constructed that it may be readily loosened by the use of a small punch and a light tap on the end of the sealing bar, when it is desired to produce a new seat.

A still further object of the invention resides in the simplicity and efficiency of the structure and economy of manufacture and installation.

With the above and other objects in view which will appear as the description proceeds, my invention consists in the novel features herein set forth, illustrated in the accompanying drawing, and more particularly pointed out in the appended claims.

Referring to the drawings in which numerals of like character designate similar parts throughout the several views,

Figure 1 is a top plan view of the device.

Figure 2 is a view in side elevation with the ported plug shown in section to illustrate the relative position of the sealing bar in sealing position, and

Figure 3 is a perspective view of the sealing bar removed from the device.

In the drawings, 1 designates the plug member, preferably composed of brass or other suitable metal, threaded at one end 2 to facilitate its application to a boiler head.

3 represents an upwardly projecting lug, integral with the plug 1 and having a transverse aperture 4 at its upper extremity, adapted to register with corresponding apertures 5 provided transversely in the bifurcated end 6 of an extension or arm 7, integral

with the weighted lever or handle 8. The extension or lug 3 is maintained in pivotal engagement with the arm 7 by means of a bolt or cotter pin 9 which projects through the apertures 4 and 5.

The plug 1 is provided with the conventional longitudinally extending port or passage 10, located centrally thereof and terminating in the reduced nipple 11 at the end opposite the threads 2.

At the junction of the extension 7 and the weighted handle 8, adjacent the nipple 11, I provide a transversely extending preferably horizontal support 12, recessed to receive an elongated cylindrical sealing bar 13, preferably composed of relatively soft material to form a seat at any point of engagement on its periphery by the nipple 11. The support 12 completely encircles the bar 13 as at 14, on at least one side of the extension 7, and is tapped, preferably in its upper wall to receive a set screw 15, whereby the sealing bar 13 is retained in place. The face of the support 12 immediately adjacent the nipple 11 is apertured as at 16 to permit said nipple to extend therethrough, for engagement with the periphery of the sealing bar 13.

The function and operation of my improved gauge cock is obvious. When the weighted handle 8 is raised, the extension 7 swings on the pivot 9 causing the sealing bar 13 to disengage the nipple 11, thus freeing the passage 10 and permitting the escape of steam or fluid therefrom. When the handle 8 is released, its weight causes the sealing bar 13 to again engage the nipple 11, the latter seating itself on the periphery of the bar 13, through the aperture 16.

When any one seat becomes worn from continued use, the thumb screw 15 is unscrewed and the cylindrical bar 13 either moved longitudinally in the transverse support 12 or rotated about its own axis to provide a new seat, when the thumb screw is again tightened to retain the bar in place.

It will thus be seen that with my improved sealing bar, a maximum number of seats may be obtained by simply a slight change in position of the bar, without removing the same from its support. In fact practically every

point on the periphery of the bar 13 may be used as a seat for the nipple 11, before the said bar is discarded for a new one.

From the foregoing it is believed that my invention may be readily understood by those skilled in the art without further description, it being borne in mind that numerous changes may be made in the details of construction without departing from the spirit of the invention as set forth in the following claims.

10 What I claim and desire to secure by Letters Patent is:—

1. A gauge cock for boiler heads and the like, including an apertured plug, a handle pivoted to said plug, and a longitudinally adjustable, elongated substantially cylindrical sealing bar mounted on said handle transversely of said apertured plug for sealing said aperture.
2. In a gauge cock including an apertured plug having a discharge nozzle, an elongated sealing bar of substantially soft material, cylindrical in cross section and located transversely of said discharge nozzle, and means whereby substantially the entire periphery of said sealing bar may be successively presented to said discharge nozzle to provide a maximum number of seats.
3. A gauge cock including an apertured plug, a weighted handle pivoted to said plug, a support member carried by said handle transversely of said apertured plug, a longitudinally adjustable, elongated substantially cylindrical sealing bar carried in said support and adapted to engage the discharge end of said plug at any point on its periphery.
4. A gauge cock including a ported plug terminating at one end in a discharge nozzle, a weighted handle pivoted to said plug, a support carried by said handle transversely of said discharge nozzle and encircling the periphery of an elongated substantially cylindrical sealing bar, a reduced opening in the wall of said support adjacent said discharge nozzle whereby the latter may extend through said wall to engage the periphery of said sealing bar.
5. A gauge cock including a ported plug terminating at one end in a discharge nozzle, a weighted handle pivoted to said plug, a support carried by said handle transversely of said discharge nozzle, an elongated substantially cylindrical sealing bar carried in said support and adjustable rotatably and longitudinally, an opening in said support adjacent said discharge nozzle whereby the latter may extend through said support to engage the periphery of said sealing bar, and means whereby said sealing bar may be adjusted so as to present any point on its periphery to said nozzle.

In testimony whereof I affix my signature.

MILLARD F. WATERS.
